UNITED STATES PATENT OFFICE

PETER E. GELDHOF, OF SYRACUSE, NEW YORK, ASSIGNOR TO SYRACUSE WASHING MACHINE CORPORATION, OF SYRACUSE, NEW YORK, A CORPORATION OF DELAWARE

IRONING MACHINE

Application filed August 15, 1930. Serial No. 475,532.

This invention relates to a new and improved ironer.

It has been found that with certain articles as, for example, collars, better and quicker results may be obtained in the ironing operation if the article is sent between the roll and the shoe first in one direction and then in another direction, and the main object of my invention is to provide an ironer in which the roll may, at will, be made to rotate in either direction.

Another object is to provide a means whereby the roll is permitted to remain at rest while the ironing shoe is operated, which is a very convenient arrangement when it is desired to press articles on the ironer.

Other objects and advantages relate to the size, shape and arrangement of parts, all as will more fully appear from the following description taken in connection with the accompanying drawings in which:—

Figure 1 is a top plan view of my improved ironer.

Figure 2 is a section on line 2—2 of Figure 3.

Figure 3 is a section on line 3—3 of Figure 2.

Figure 4 is a section on line 4—4 of Figure 3.

Figure 5 is a perspective view of one end of the roll drive shaft.

Figure 6 is a section on line 6—6 of Figure 1.

Figure 7 is a section on line 7—7 of Figure 9.

Figure 8 is a section on line 8—8 of Figure 7.

Figure 9 is a section on line 9—9 of Figure 2.

Figure 10 is a section on line 10—10 of Figure 7.

Figure 11 is an elevation of the connection between the outer end of the roll drive shaft and the roll.

My ironing machine 1 comprises a gear casing 2 having a laterally extending boss 3.

A supporting tube 4 has one end positioned in boss 3 and extends laterally from gear casing 2. In the inner end of tube 4 is positioned a ball bearing 5 and a similar ball

bearing 6 is positioned in the outer end of tube 4.

A drive shaft is journaled in bearings 5 and 6 with its outer end extending beyond bearing 6. The construction of the inner end of shaft 7 will be hereinafter described.

An ironing roll 8 having the usual fabric covering 9 carries adjacent its inner end an internal plate 10 provided at its central portion with a bearing member 11 in which tube 4 is positioned.

The outer end of roll 8 carries a similar plate 12 having a bearing member 13 in which the outer end of tube 4 is positioned. On the outer end of shaft 7 is secured, as by a pin 14, an offset arm 15 which has its outer end secured to plate 12, as by a pin 16, so that the rotary movement of shaft 7 will be communicated to roll 8.

A second laterally extending boss 17 has positioned therein in parallel relation to tube 4 a second supporting tube 18. The outer end of tube 18 is supported in a saddle member 19.

A shaft 20 extends through tube 18 with its inner end extending beyond tube 18 into gear casing 2. The outer end of shaft 20 extends beyond the outer end of the tube 18 and has secured thereto, as by a pin 21, an ironing shoe support 22.

On the upper end of support 22 is pivotally mounted on a pin 23 a yoke 24. An ironing shoe 25 having positioned therein the usual heating unit 26 is secured to yoke 24, as by bolts 27, and has a lead 26' so that it may be connected to a source of potential.

Yoke 24 is so designed in relation to the support as to limit the downward pivotal movement of yoke 24 when shoe 25 is out of contact with roll 8.

An axially movable shaft 28 has one end journaled in a bearing 29 on one side of casing 2 and has the other end journaled in the bearing 30 in the opposite side of casing 2.

As indicated in dotted lines in Figure 3, bearing 30 has its inner face formed into a cam surface 31 for a purpose hereinafter to be described.

A motor 32 is secured to casing 2 and has a lead 32' so that it may be connected to a

source of potential. The armature shaft 33 of the motor 32 extends into casing 2 with its axis normal to the axis of shaft 28.

5 The inner end of armature shaft 33 carries a worm 34. A worm gear 35 is rotatably mounted on shaft 28 and is in mesh with worm 34. Worm gear 35 has a laterally extending hub 36.

Secured to the hub 36 of worm gear 35, as 10 by a pin 37, is a circular toothed clutch member 38. Adjacent clutch member 38 and keyed to shaft 28, as by a key 39, is a member 40 having a circular portion 41 eccentrically positioned with relation to shaft 28.

15 The keyway in member 40 is elongated to permit the movement therein of key 39, key 39 being rigidly secured in shaft 28.

Referring to Figure 7, a dog 42 is pivotally mounted on member 40 on a pivot pin 43. Dog 20 42 carries a depending lug 44 adapted to register with one of a plurality of circumferentially spaced slots 45 in member 38.

25 Referring to Figure 8, a plate 46 is also pivotally mounted on member 40 on pivot pin 43 and conforms in shape and position approximately to dog 42.

30 One end of plate 46 is bent, as shown at —a— in Figure 10, which bent portion is in spaced relation to dog 42.

35 A spiral spring 47 is interposed between the end of plate 46 and dog 42. The upper edge of plate 46 is also bent outwardly, as shown at —b— on Figure 10, above the upper end of dog 42 to limit the upward movement of dog 42 in relation to plate 46 under the action of spring 47.

40 A spiral spring 48 has one end secured to member 40, as by a pin 49, and has the other end secured to end of plate 46 to normally urge plate 46, carrying with it dog 42, about the pivot 43 to bring the lug 44 into engagement with a slot 45 in clutching member 38.

45 For the purpose of holding dog 42 out of engagement with clutch member 38 so that member 40 may be at rest, I provide a member 50 having its upper end secured to the inner end of a rock shaft 51 mounted in casing 2.

50 On the outer end of shaft 51 is provided a hand lever 52 to provide a convenient means for manually rocking shaft 51.

55 The lower end of the member 50 is adapted to be moved into and out of the path of movement of plate 46 and dog 42 and is so dimensioned that when it is in such path of movement plate 46 and dog 42 will be held in such a position that the lug 44 will be out of registration with the clutch member 38.

60 When the member 50 is in the path of movement of plate 46 and the latter is brought into contact therewith, the spring 47 will be compressed and the dog 42 will be raised to carry lug 44 out of registration with clutch member 38.

65 The spring 47 will then expand, moving

the dog 42 further about the pivot 43 to position the lug 44 in spaced relation to the clutch member 38 so that there will be no possibility of the two contacting while the clutch member 38 continues to rotate. This movement of plate 46 and dog 42 takes place when the end of plate 46 to which the spring 48 is attached contacts with the member 50.

70 When the opposite end of plate 46 contacts with member 50, the same movement of parts will take place due to the fact that such end of plate 46 is held against further movement and this will cause plate 46 to be moved about its pivot to compress spring 47 and move lug 44 out of registration with clutch member 80 75 38.

Spring 47 will then expand to further move dog 38 about its pivot to carry lug 44 to a position in spaced relation to clutch member 85 38.

The face of gear 35 opposite to that which carries the hub 36 is provided with a plurality of circumferentially spaced female clutch members 53. Adjacent the face of gear 35 which carries the clutch members 53 is rotatably mounted on sleeve 28' a gear 54 carrying a plurality of male clutch members 55 adapted to co-act with the clutch members 53 in gear 35.

90 Adjacent the face of gear 54 which carries the clutch members 55, the shaft 28 is formed with an annular groove 56 in which is positioned a circular disk 57 which bears against the face of sleeve 28'.

95 Encircling shaft 28 and boss in casing 2 is a spiral spring 58 which normally urges sleeve 28' and gear 54 into clutching engagement with gear 35.

100 Referring to Figures 3, 4 and 5, the inner end of shaft 7 carries a collar 59 and has a 105 reduced threaded end 60.

The inner end of shaft 7 is slotted, as shown at —c— on Figure 5, and has an internally extending aperture 61 extending from the end of shaft 7 beyond collar 59.

110 A gear 62 is rotatably mounted on shaft 7 abutting against the inner face of collar 59. Gear 62 has a plurality of circumferentially spaced female clutch members 63 positioned outside of the periphery of collar 59.

115 A second gear 64 is rotatably mounted on shaft 7, abutting against the outer face of collar 59. Gear 64 has on its face towards gear 62 a plurality of circumferentially spaced female clutch members 65 positioned outside of the periphery of collar 59. Gear 64 is held against axial displacement by a nut 66 on the threaded end 60 of shaft 7. Gear 64 is in mesh with gear 54. Gear 62 is in mesh with gear 67 carried on a stub shaft 68. Gear 67 120 is in mesh with gear 54. The rotation of gear 54 will cause gear 64 to be rotated in one direction whereas the rotation of gear 54 through gear 67 will cause the rotation of gear 62 in the opposite direction.

A shaft 69 is slidably mounted in the apertured end of shaft 7 and carries on its forward end a double male clutch member 70 which is positioned in slot —c— and extends 5 outwardly therefrom on both sides of collar 59.

Member 70 carries on one end a pin 71 which extends outwardly from both sides of member 70 and which is adapted to enter an 10 aperture 63 in gear 62, or an aperture 65 in gear 64 depending on the direction of the axial movement of shaft 69.

The other end of member 70 carries a similar pin 72 which is also adapted to enter 15 either an aperture 63 or an aperture 65. The relation of parts is such that the member 70 may be positioned between gears 62 and 64 with the pins 71 and 72 out of registration with both apertures 63 and 65.

20 The outer end of shaft 69 is enlarged and is provided with an annular groove 73 in which is positioned a shifting fork 74 on the lower end of a lever 75. Lever 75 is pivoted at 76 to casing 2, the upper end of lever 75 25 extending upwardly through an aperture 77 in the top of casing 2.

A coil spring 78 has one end secured to the casing 2 and has the other end secured to a shoulder 79 on lever 75. The relation of 30 parts is such that when the upper end of the lever 75 is moved in one direction, spring 79 will cross pivot 76 and tend to hold lever 75 in that position. Similarly, when the upper end of lever 75 is moved, the greatest distance in the opposite direction, spring 79 35 will again cross pivot 76 and tend to hold lever 75 in that position.

As shown in Figure 1, I provide in the 40 side of aperture 77 through which the upper end of lever 75 extends, three slots 80, 81 and 82 in which the upper end of lever 75 may be positioned to secure it in a selected one of three positions.

When the upper end of lever 75 is moved 45 towards roll 8, the shaft 69 will be moved outwardly in shaft 7 to bring the pins 71, 72 into registration with aperture 65 in gear 64, thus locking gear 64 to shaft 7.

Similarly, when the upper end of shaft 50 55 75 is moved away from roll 8, the farthest extent possible, the shaft 69 will be moved inwardly in shaft 7 to bring the pins 71 and 72 into registration with apertures 63 in gear 62 so that gear 62 will become locked to shaft 7.

If it is desired to leave roll 8 at rest, the 60 upper end of shaft 75 is placed in notch 81 which will hold member 70 in a position where the pins 71 and 72 will not be in registration with either aperture 63 or aperture 65.

It will be understood that when the upper 65 end of lever 75 is moved to bring pins 71 and 72 into registration with aperture 63, the upper end of lever 75 will be placed in slot 82 to lock it in position.

Similarly, when the upper end of lever 75 is moved to bring pins 71 and 72 into registration with aperture 65, such upper end of lever 75 will be placed in slot 80 to lock it in position.

70 On the inner end of shaft 20 is secured, as by a pin 83, a crank 84 having opposed jaws 85 and 86 which encircle the cam member 41.

The rotary movement of member 40 on which is eccentrically mounted the cam member 41 will cause the crank 84 to be oscillated and this oscillating movement will be communicated to the shaft 20 upon which is mounted the ironer shoe support 22.

75 The oscillating movement of shaft 20 will cause the shoe 25 to be moved into and out of contact with the roll 8.

In order to perform the ironing operation 80 properly, it is necessary that the shoe 25 be held in contact with the roll 8 under some degree of pressure.

In order to accomplish this result in the 85 simplest way, the shaft 20 is made of a material which is sufficiently torsionally resiliant as to become slightly distorted when the shoe 25 moves into contact with the roll 8 and thus through its inherent resiliency exert a certain degree of pressure by the shoe 25 90 against the roll 8.

The relation of parts is such that when 95 the member 50 is in the path of movement of the plate 46, the clutch member 40 will come to rest with the high side of the cam 41 in either the extreme low position or the extreme high position depending upon which end of plate 46 contacts with member 50.

When the high side of cam 41 is in the 100 down position, the crank 84 will also be in the down position and the shaft 20 will be in a position to hold the shoe 25 under pressure contact with the roll 8.

When the parts are in this position, the 105 key 39 on shaft 28 will be in registration with the low side of the cam surface 31 on bearing member 30 so that gear 54 will be in clutching relation with gear 35 so that the roll 8 may be rotated in either direction by manipulation of the lever 75.

When the clutch member 40 comes to rest 110 with the high side of the cam 41 in the raised position, the crank 84 will also be in the raised position and the shaft 20 will be in such a position that the shoe 25 will be out of engagement with the roll 8.

When the parts are in this position, the 115 key 39 will be in registration with the high side of cam surface 31 and the gear 54 will have been disengaged from gear 35 due to the axial movement of the shaft 28 and the roll 8 can be rotated by hand.

120 It will thus be seen that by the manipulation of handle 52 to rock shaft 51, the member 50 may be moved into and out of the path of movement of plate 46 at the will 125

of the operator. It will also be seen that the roll 8 may be caused to rotate in either direction by the manipulation of lever 75 or, if desired, the lever 75 may be positioned so that the clutch member 70 is out of engagement with both gear 62 and gear 64 so that the roll 8 will be at rest while the shoe 25 moves into and out of pressure contact with roll 8. This relation of parts is particularly convenient when it is desired to perform a pressing operation on an article.

For the purpose of controlling the operation of the motor 32, I provide in casing 2 a switch 87.

I have here described a particular type of ironing machine and operating mechanism therefor, but it will be understood that my invention may be used in combination with other types of operating mechanism in order to obtain a structure in which the direction of rotation of the roll may be varied as desired or the roll may be left at rest while the remainder of the mechanism operates.

It will also be understood that numerous changes in the size, relation and arrangement of parts may be made without departing from the spirit of my invention for although I have shown and described a specific structure and form and relation of parts as an exemplification of an embodiment of my invention, I do not desire to restrict myself to the exact size, shape or arrangement of parts, as various changes may be made within the scope of the appended claim.

I claim:

In an ironing machine, in combination, a roll, a single drive shaft for the roll, a shoe adapted to be moved into and out of pressure contact with the roll, means for operating the shoe, said drive shaft projecting from one end of the roll, a casing into which the projecting shaft end extends, and mechanism confined within the casing for rotating and controlling the direction of rotation of the shaft and roll including spaced gears rotatably mounted on the shaft end, a clutch member non-rotatably mounted on the shaft and adapted to be moved into and out of clutching engagement with a selected one of said gears, a counter shaft parallel with the drive shaft, a gear on the counter shaft in mesh with one of the first mentioned gears, a second counter shaft below and parallel with the drive shaft, a gear on the second counter shaft in mesh with the gear on the first named counter shaft and with the other of the first mentioned gears, means for rotating the gear on the second mentioned counter shaft and means on the second countershaft for actuating the shoe operating means.

In witness whereof I have hereunto set my hand this 6th day of August, 1930.
